CLAIM

The ornamental design for a cross structure, for a small jewel, costume jewelry, a church cross or a statue as shown and described.

DESCRIPTION

FIG. 1 is a top plan view of a first embodiment of a cross showing the above-identified invention;

FIG. 2 is a bottom plan view of the embodiment of FIG. 1; FIG. 3 is a front elevated view of the embodiment of FIG. 1;

FIG. 4 is a back elevated view of the embodiment of FIG. 1;

FIG. 5 is a right side elevated view of the embodiment of FIG. 1;

FIG. 6 is a left side elevated view of the embodiment of FIG. 1;

FIG. 7 is a perspective view of a second embodiment of the present invention.

FIG. 8 is a perspective view of a third embodiment of the present invention.

FIG. 9 is a perspective view of a fourth embodiment of the present invention.

FIG. 10 is a perspective view of a fifth embodiment of the present invention; and,

FIG. 11 is a perspective view of a sixth embodiment of the present invention.

The inventor disclaims surface indicia or colors in the drawings.
